FIG.1

FIG.2

FIG.3

FIG.4

FIGURE 1 is a front, elevational view of a combined ball point pen and key chain, constructed in accordance with my invention, the back being similar in design to the front thereof and the pen being shown in the retracted position;

FIGURE 2 is a front, elevational view of the combined ball point pen and key chain shown in FIGURE 1 but shown in the writing position;

FIGURE 3 is a side, elevational view of the combined ball point pen and key chain, illustrated in FIGURE 2; and

FIGURE 4 is a top view of the combined ball point pen and key chain illustrated in FIGURE 2.

The essential features of my design reside in those portions shown in full lines in the drawings.

I claim:

The ornamental design for a combined ball point pen and key chain, substantially as shown and described.
